UNITED STATES PATENT OFFICE.

FRANK KLASSEN, OF MCPHERSON, KANSAS.

GUIDING DEVICE.

1,310,664.

Specification of Letters Patent. Patented July 22, 1919.

Application filed August 26, 1918. Serial No. 251,459.

To all whom it may concern:

Be it known that I, FRANK KLASSEN, a citizen of the United States, residing at McPherson, in the county of McPherson and State of Kansas, have invented certain new and useful Improvements in Guiding Devices; and I do declare the following to be a full, clear, and exact description of the invention, such as will enable others skilled in the art to which it appertains to make and use the same.

This invention relates to guiding devices, and it relates more particularly to an improved guiding attachment for auto-tractors and the like.

One object of this device is to provide a device of this character which is adjustable so as to be quickly and easily attachable to different styles and sizes of automobiles or tractors, and which is equally effective for guiding the different kinds and sizes;

Another object is to provide a device of this character in which the guiding operation is entirely automatic, and which guides the tractor or automobile around curves as well as along a straight path;

Another object is to provide a device of this character having a controlling spring that coöperates with other elements in effecting the automatic guiding and which is also effective for holding the guide-pole in and out of its operative position;

Another object is to provide a device of this character of which all the elements are united in a unitary structure and a simple attachment that can be attached and adjusted by any person of ordinary ability;

Another object is to provide a device of this character which comprises comparatively few and simple parts which may consist mainly of unmachined castings, forgings, stamping and stock material, and may be manipulated at a slight cost;

Another object is to provide a device of this character which is strong, durable, and thoroughly practical.

Other objects and advantages may become apparent to persons who read the following details of description in connection with the accompanying drawings, in which:

Figure 1 is a top plan view illustrating the front portion of an ordinary automobile or tractor having my improved automatic

guide attachment attached and in its working position; 55

Fig. 2 is a side elevation of the mechanism shown in Fig. 1, parts of the tractor being broken out so as to more clearly show the structure of my improved guiding device; 60

Fig. 3 is an enlarged vertical sectional view, the section being taken along the line 3—3 of Fig. 1;

Fig. 4 is an enlarged sectional view, the section being taken along the line 4—4 of Fig. 1;

Fig. 5 is an enlarged sectional view, the section being taken along the line 5—5 of Fig. 1; 70

Fig. 6 is a perspective detail view, illustrating a number of the component parts of my invention separated but respectively positioned to show the correlation to one another; and 75

Fig. 7 is a perspective view of one of the clamping elements whereby my improved jointed steering device is operatively connected to the ordinary steering mechanism of an automobile or the like. 80

Referring to these drawings in detail, in which similar reference characters correspond with similar parts throughout the several views, the automobile or tractor *a* is of ordinary construction and will not be described in detail except to mention the jointed front axle which constitutes the stub-axle *b* and the intermediate axle member *c* which is substantially stationary with the main frame; said stub-axles being provided with lateral arms *d* which are pivotally connected through the medium of a steering link *e*, which may be connected to the other elements of an ordinary steering mechanism in any manner desired. However, when it is desired to use an ordinary automobile or tractor with my improved automatic steering device, all of the ordinary steering mechanism may be omitted or removed, (if desirable) except the elements *b*, *d* and *e*. 95

The attachment which constitutes the present invention consists of three clamps 8, 9 and 10, a lever 11, an arm 12, a guide-pole 13, a spring 14 and such adjuncts as will be hereinafter referred to. 100

The clamp 8 comprises an apertured plate 15 and two U-bolts 16 with their correlated nuts. This clamp element embraces the axle

- a* between the stub-shafts *b*, the plate 15 preferably fitting against the lower surface of the axle and being provided with a stud 17 which is preferably threaded at both ends and comprises a pivot element which coöperates with the plate 15 for supporting the lever 11. The rear arm of the lever 11 is longitudinally slotted at 18 for the reception of a pin 19 which is adjustable longitudinally of the slot 18, the pin 19 having a screw-threaded end which extends through the slot 18 and engages with a nut 20 which coöperates with the pin for holding the latter in each of its adjustments. The pin 19 normally extends upward through a slot 21 of a plate 22 which constitutes a portion of the clamp element 9, a pair of U-bolts 23 and their correlated nuts constituting the other elements of this clamp. From the foregoing disclosure of the elements 9 and 19, in connection with the slots 18 and 21, it will be seen that the clamp 9 may be adjusted longitudinally of the link *e*, and the pin 19 may be adjusted longitudinally of the slot 21 while adjusting said pin 19 longitudinally of the slot 18, thereby effecting the substantial lengthening and shortening of the leverage which operates the steering link *e*.
30. The front arm of the lever is provided with a normally horizontal pivot bearing 24 through which a pivot 25 extends, this pivot also extending through the apertured ears 26 of the arm 12, so that said arm may be swung vertically with relation to the lever 11. The arm 12 is apertured at 27 for the reception of a U bolt 28 which engages the rear end of the pole 13. Moreover, the arm 12 is apertured or slotted at 29 for the reception of a U-bolt 30. This U-bolt 30 extends through an apertured clamping block 31 which is provided with a V-notch 33. The slot 29 is longer than the distance across the parallel arms of the U-bolt 30, so that this U-bolt may have movement longitudinally of the slot 29. In thus moving the U-bolt longitudinally of the slot 29, the guide pole 13 is moved laterally with relation to the arm 12; or, in other words, the front of the guide pole is swung about the point at which it is connected to the arm 12 by the U-bolt 28, said U-bolt being sufficiently large to allow such movement.
- It will be seen that the U-bolt 30 and its correlated nuts, together with the clamping block 31 constitute an adjusting clamp which coöperates with the clamp elements 28 and its correlated nuts for holding the guide pole 13 in each of its adjusted positions.
60. The guide pole 13 is preferably formed with a curved end which constitutes a runner and is slidable along the horizontal and vertical surfaces of a furrow, and such furrow constitutes an extraneous guide which

coöperates with the guide pole for swinging the guide arm 12 and guide lever 11 horizontally.

The spring 14 has one end connected to the clamp 10 and has its other end connected to the vertically swinging arm 12, the point of connection to the clamp 10 being disposed in a lower plane than the point of connection to the arm 12. This feature of the invention is clearly shown in Fig. 2, and its effect is to draw the arm 12 and pole 13 downward so as to keep the curved end of the arm 12 against the horizontal surface or bottom of the furrow. In order to effect this arrangement of the spring 14 and arm 12, the clamp 10 comprises a plate 34 having a depending apertured arm 35 to which the spring 14 is secured. The plate 34 is secured to the axle element *c* by means of the U-bolts 36 and their correlated nuts, and it is obvious that the spring 14 may be tensioned by loosening the nuts, sliding the clamp 10 along the axle element *c*, and then tightening the nuts.

The several clamp elements 8, 9 and 10 may be quickly and easily connected to the axle and steering link of an automobile by removing the respective nuts from the U-bolts, placing U-bolts over the elements *c* and *e*, positioning the several plates in engagement with their respective sets of U-bolts, and engaging the nuts with the respective U-bolts. Having thus attached the device, the correct relation of parts may quickly and easily be attained by adjustment of the clamping elements along the automobile elements *c* and *e* and by lateral adjustment of the elements 12 and 13 with relation to one another.

In order that the device may be rendered inoperative, I provide a cord, wire or cable 37 which is attached to the pole 13 at 38 and extends over a sheave wheel 39 to a convenient position to be manipulated by the driver of the automobile.

Although I have described this embodiment of my invention very specifically, it is not intended to limit my invention to these exact details of construction and arrangement of parts, but I am entitled to make minor changes without departing from the inventive idea disclosed in the foregoing description and following claims.

What I claim as my invention is:

1. An automobile guiding device comprising a supporting element, a lever pivoted thereon and movable horizontally on its pivot and adapted to be connected to the automobile's steering mechanism so as to actuate the latter, an arm pivotally mounted on said lever and extending along the path of travel of the automobile and movable vertically on its pivot, a pole provided with an element to contact with an extraneous guide, said pole having one end portion ly-

ing against and longitudinally parallel with said arm, and means for adjustably securing said pole to said arm to permit lateral adjustment of said pole on said arm.

- 5 2. In an adjustable guiding attachment for automobiles, a support attachable to and adjustable on the intermediate part of the front axle of the automobile, a member attachable to and adjustable on the steering 10 link of the automobile, a spring-connection attachable to and adjustable on said axle, a jointed guiding device connected to said member and pivoted on said support and adapted to be guided by an extraneous guide 15 and thereby to be swung horizontally on its pivot and transmit motion to said steering link through said member, and a retractile spring connected to said jointed guiding device and to said spring-connection.
- 20 3. In an adjustable automatic guide for automobiles, the combination of a lever, means for securing said lever to an automobile and allowing horizontal movement of the lever, means for operatively connecting 25 said lever to the ordinary steering mechanism of the automobile, an arm pivotally mounted on said lever and swingable vertically on its pivot, a pole provided with an element to contact with an extraneous guide, 30 means for adjustably connecting said pole to said arm to permit lateral adjustment of the pole on the arm, and means for retaining said arm in its operative position.

4. In an adjustable automatic guide for 35 automobiles, the combination of a lever,

clamping means for securing said lever to an automobile and allowing horizontal movement of the lever, adjusting means for operatively connecting said lever to the ordinary steering mechanism of the automobile, an 40 arm pivotally mounted on said lever and swingable vertically on its pivot, a pole provided with an element to contact with an extraneous guide, means for adjustably connecting said pole to said arm to permit lateral adjustment of the pole on the arm, and a spring for controlling movement of said arm.

5. In an adjustable automatic guide for automobiles, a lever, means for securing said lever to an automobile and allowing horizontal movement of the lever, means for operatively connecting said lever to the ordinary steering mechanism of the automobile, an arm pivotally mounted on said lever and swingable vertically on its pivot, a pole provided with an element to contact with an extraneous guide, means for attaching said pole to said arm and for allowing lateral adjustment of the pole relative to the arm, a 55 spring for controlling movement of said arm, and means adjustably clamped to said automobile and adapted to hold and tension said spring.

In testimony whereof I have hereunto set 60 my hand.

FRANK KLASSEN.
